COMBUSTION DEVICE

William W. Peck, Muncie, Ind.

Application August 26, 1935, Serial No. 37,819

2 Claims. (Cl. 110—45)

This invention relates to improvements in combustion devices and more particularly to retorts such as used in furnaces, or boilers, equipped with automatic solid fuel stokers.

One of the difficulties encountered in the burning of pulverized solid fuel, such as coal, in retorts placed in the fire boxes of furnaces and boilers, wherein both fuel and air are automatically conducted to the retort is the building up of a "mushroom" formation of coke at the top of the fuel bed which reduces the efficiency of the apparatus as a combustion device. These so-called coke "mushrooms" appear as the result of incomplete combustion of the coal due to an insufficiency of air supplied to a part of the body of coal in the retort and therefore they generally appear at the central portion of the coal bed which is farthest away from the tuyère openings.

It is therefore an object of my invention to provide an improved retort for solid fuel stokers wherein the formation of coke "mushrooms" on the burning fuel bed is eliminated.

Another object is to provide an improved retort that is so shaped as to cause the distribution of air admitted thereto into direct contact with the entire body of coal contained in the retort.

A further object is to provide an improved retort as described wherein rupture or breakage of the perforated tuyère wall of the retort through thermal expansion is reduced to a minimum.

A further object is to provide a retort, as described, which is so shaped as to distribute the live coal bed over a relatively large area within the fire box of the furnace, or boiler, without materially increasing the fuel capacity of the retort.

Other objects, the advantages and uses of the invention will become apparent after reading the following specification and claims, and after consideration of the drawing forming a part of the specification, wherein:

Fig. 1 is a diagrammatic side elevation of an automatic coal stoker equipped with my improved retort;

Fig. 2 is a top plan view partially in section illustrating the retort in Fig. 1, and

Fig. 3 is a sectional view along the line III—III 50 of Fig. 2.

I have selected for illustration herein three species of my improved retort.

With reference to Figs. 1 to 3, the retort is intended for use with any type of solid fuel stoker such as a pulverized coal stoker illus-

trated in outline in Fig. 1. Such a stoker may comprise a hopper 2, mechanism, contained within a housing 3, for driving a coal feed screw, indicated in dotted line at 4, by means of which coal from the hopper 2 is conveyed into the bowl or tuyère ring of the retort through an interconnecting tube 5.

My improved retort as illustrated in Figs. 1 to 3 inclusive, comprises two parts; a tuyère ring 7 and a wind box 8, both of which may be constructed of cast iron. The wind box 8 has formed in conjunction therewith a tubular portion 9, adapted to form a continuation of the coal feed tube 5, and containing the coal feed screw 4. The innermost end of the portion 9 communicates with the bottom of the retort. At one side of the tubular passage 9 is a duct 11 through which air may be admitted from a blower, forming a conventional part of the stoker mechanism in the housing 3, into that portion 14 of the wind box 8 surrounding the bottom wall 10 of the retort and the perforated side wall 12 of the tuyère ring. It is intended in this form of the retort that the wind box 8 shall rest directly upon some supporting surface, as indicated at 13, and therefore such support forms the bottom wall for the air chamber 14 surrounding the retort wall at the inner end of the air duct 11.

A clean-out passage 16 is provided on the opposite side of the fuel inlet tube 9 which also communicates with the air chamber 14 and is normally closed by a cap 17. This passage is employed for the purpose of removing powdered coal from the air chamber, from time to time.

The tuyère ring 7 may be fixed in place upon upstanding wall extensions 18 of the wind box 8, by means of bolts 19, so that it is not necessary to remove the retort from the furnace to replace or repair the tuyère ring; but instead the ring may be detached from the wind box and lifted upwardly and through the fire door 22 of the furnace, thus saving the removal and replacement of masonry such as required properly to seal the retort in the furnace.

It will be noted that the contour of the retort, as defined by its inner side wall 12, is substantially "heart-shaped" with the narrow end in register with the terminus of the fuel inlet tube 9. This contour provides a cleavage surface 23 which serves to divide the incoming stream of pulverized coal into two parts forming areas indicated at 24 and 25, respectively. The dividing of the coal stream in this manner serves a two-fold purpose:

(A) There is a mechanical disturbance of the

coal bed at the cleavage surface 23, which is substantially at the middle point of the aggregate bed area, that functions to break up any coke formation which may have started to form.

5 (B) The greatest distance between the mid-portion of the coal bed and the adjacent slotted tuyère wall is reduced, thus to assure complete penetration of the bed of coals by the incoming air admitted through the tuyère slots 28 in the 10 wall 12. This condition likewise discourages the formation of coke "mushrooms" because it encourages complete combustion, both under natural and forced draft.

As heretofore stated, both tuyère ring 7 and 15 wind box 8 may be formed of cast iron, preferably gray iron, and that wall of the wind box forming the bottom wall 10 of the retort and tuyère wall 12 may be of relatively thin construction, thus expediting heat radiation which is 20 highly desirable in keeping the wall cool to prolong the useful life of the retort.

Another and important feature of my improved retort is the contour and arrangement of the plurality of tuyère slots 28 formed through 25 the tuyère wall 12. These slots are arranged in vertically spaced groups throughout the entire wall surface, the slots of one group being staggered with respect to the slots of the adjacent groups. This arrangement greatly increases the 30 limit of elasticity of the tuyère wall under thermal expansion beyond which rupture or breakage of the wall may take place. Under actual working conditions I have observed local bulging of the tuyère wall, under thermal expansion, to an extent which would have resulted in rupture or breakage were it not for this staggering of the slots and consequent staggering of the portions between the slots. Another feature of the retort is the formation of the tuyère slots 35 with their side walls 31 diverging in the direction of the air chamber. This simple yet highly effective arrangement precludes the choking of the tuyère slots by fuel or ash which may pass

into the slots from within the retort. Such material having once entered the slot must necessarily fall into the air chamber 14 where it may be removed at leisure through the clean-out passageway 16.

I claim as my invention:

1. A combustion device comprising a cast ferrous metal retort comprising an enclosing wall sloping downward and inward, said retort being approximately heart-shaped in horizontal 10 contour and having an opening adjacent the bottom thereof at the narrow end thereof for admitting pulverized coal, whereby coal admitted to said heart-shaped retort will be divided into two angularly divergent streams, and means providing an air chamber surrounding the retort and having an air inlet through which air under pressure may be admitted to the chamber, the wall of said retort being further formed with a plurality of elongated tuyère slots therethrough 15 arranged in vertically spaced groups, the slots of one group being staggered relative to the slots of the adjacent group.

2. A combustion device comprising a cast ferrous metal retort approximately heart-shaped in horizontal cross section, said retort comprising an enclosing wall sloping downward and inward, with the wall at the central portion of the retort sloping downward toward the narrow end of the retort to provide a dividing ridge at a point beyond the mid-section of the retort, whereby to induce divergence and elevation of pulverized coal admitted to the retort through the narrow end thereof, means providing an entrance for pulverized fuel at the narrow end of the retort adjacent the bottom thereof and in alignment with said dividing ridge, and means providing an air chamber surrounding the retort and having an air inlet opening through which air under pressure may be admitted, the wall of the retort being provided with a plurality of tuyère slots therethrough.
